RENEWABLE FUSE STRUCTURE

John B. Griffith, Jamestown, N. Y.

Application July 29, 1937, Serial No. 156,396

1 Claim. (Cl. 200—131)

This invention relates to a renewable fuse structure, and is more particularly concerned with simplification and reduction of the number of parts therein.

One of the features of the present invention is the provision of a renewable fuse structure comprising an external tube of insulating material and an internal rigidly-assembled support for a fusible link, these parts being capable of quick assembly and disassembly by a simple threaded joint or the like.

Another feature of the present invention is the provision of an external insulating body having a shoulder therein, together with an assembled holding structure for the fusible link, the holding structure comprising sealing means engaged with said shoulder when assembled and also including interengaging screw threads on said external member and on said holding structure for assuring the desired relationship.

With these and other features as objects in view as will appear in the course of the following specification and claim an illustrative form of construction according to the present invention is shown in the accompanying drawing in which:

Figure 1 is a side elevation of a renewable fuse structure according to this invention.

Figure 2 is an axial diametrical section through the same substantially on line 2—2 of Figure 1.

Figure 3 is an exploded view showing parts of one end of the holding structure.

Figure 4 is an enlarged sectional view of the other end indicating a gas escape channel.

Figure 5 is a perspective view of a fusible link for employment in the device.

Figures 6 and 7 are views showing modifications in the construction of the structure.

In the drawing, the renewable fuse structure is illustrated as comprising an external insulating body which is shown as a sleeve 10 of vulcanized fiber in the form shown by Figures 1 to 4. For reasons of cheapness, it has been found advantageous to make this tube from a piece of tubing having an external diameter desired for the finished fuse structure and having an internal diameter slightly greater than the width of the contact terminal blades. Such tubing is commercially available. The tubing is cut to the desired standard length, and is then bored to increase the internal diameter from one end up to an inwardly extended flange 10a which provides a shoulder as will be described hereinafter. This boring operation can be quickly and simply effected, and is followed by a similar threading operation to provide threads 10b at the open larger end of the

tube. It is preferred to form this sleeve of insulating and infusible material such as the vulcanized fiber referred to. When formed, it is also preferred to coat and seal the surface of this material by the employment of a liquid coating composition which is non-inflammable under the conditions of service, and is not changed by the action of heat or gases released at the time of disruption: such a composition is referred to in my co-pending application, Serial Number 156,395, filed of even date herewith and entitled renewable fuse structure.

A supporting structure for a fusible link is introduced into this tube. This structure comprises the contact terminal blades 11, 12 which are of standard size and shape for particular sizes of fuse structures, with respect to capacity. As shown in Figures 3 and 4, each blade 11, 12 is narrowed down by providing shoulders 11b, 12b so that a narrow extension or tongue 11a, 12a is provided at the interior end, and having a hole 11c, 12c. It will be noted that these two blades 11, 12 may be identical in size and shape.

The blade 11 has its narrow portion 11a passed through and tightly fitting in the correspondingly-shaped slot 13a of a closure disc 13. This disc has an external diameter which is greater than the original internal diameter of the outer tube 10 when formed as above described, and less than the internal diameter of the bore hole 30 formed therein.

The tongue 11a of a contact blade 11 extends inside of the disc 13 and overlaps a spacer member 14 which appropriately may be of fiber material. The length of this spacer 14 is dimensioned to the desired distance between the disc 13 and a corresponding head 20 at the other end of the structure. Apertures are provided therein at such distances that, when these apertures are aligned with the holes 11c, 12c, the ends of spacer member 14 abut against the disc 13 and the head 20. These holes are appropriately spaced according to the dimensions of the fusible link FL (Figure 5) to be employed. At the other end, the head 20 has a threaded exterior for engagement with the screw threads 10b and has a slot 20a closely receiving the tongue 12a of the blade 12. It is unnecessary to have the head 20 solid, and it may be hollowed out, preferably from the exterior as shown in Figure 4.

The rules of the board of fire underwriters require that such fuse structures should be so devised that there is no puff or blast of hot gas at the time of disruption. With the present arrangement, the threaded engagement of the

threads 20b on the head 20 with the threads 10b causes a seal to be effected between the disc 13 and the shoulder 10a. Further, it is preferred to cut the threads 10b and the threads 20b both with sharp bottom or V-threads. However, the bore in the body 10 is made larger in diameter than the base or root diameter of the threads 20b so that a small spiral passage remains when the parts are threaded together, to permit slow adjustment of pressure conditions such as those occurring naturally in operation or created by the thermal heating of air, etc., within the fuse structure upon disruption. It will be noted that the parts may be cheaply and easily constructed so that the normal tolerances will provide joints which have crevices of such reduced dimensions that the rules are satisfied.

In using the structure, the support for the fusible link is assembled by passing the bolts 16 through washers 17, through the apertures in the spacer 14, and through the reduced portions 11a, 12a. A further washer 18 and a nut 19 is then placed upon each bolt. It is now possible to slip the fusible link FL (Figure 5) beneath the washer 18, this link being held away from the spacer member by the thickness of the reduced portion or tongue 11a, 12a (Figure 2). The nuts 19 are then tightened and the support with the link secured thereto may then be introduced into the tubular housing 10. The threads are brought together and are tightened by the usual relative rotations until the disc 13 is pressed tightly against the shoulder 10a.

The device is used in the normal manner. When the fusible link has been disrupted, the entire device can be removed from the fuse block and the parts unscrewed and separated. The nuts 19 are released and fragments of the fusible link FL ejected. A new fuse link is slipped beneath the washers 18, the nuts are tightened again, and the assembly is screwed back into the tubular housing 10.

While a cheap and advantageous construction has been described above in respect to forming the tubular housing 10 integrally by boring and tapping a piece of fiber, it is obvious that this construction may be provided in other ways. From Figure 6, for example, it will be noted that

a tubing 10x having a larger interior diameter may be employed, together with a short ring 10y for providing a shoulder to receive the disc 13. The ring 10y may be held in position by cementing as shown at the joint 10w. Also small rivets 5 or pins 30 may be introduced if desired.

In Figure 7 the ring 10y is illustrated as being of conductive material, and the pins 30 pass to the exterior and may be utilized for contact with a neon light terminal to determine whether or not the fusible link has been disrupted.

It is obvious that the invention is not limited solely to the forms of construction shown but that it may be varied in many ways through the scope of the appending claim.

I now claim and desire to secure by United States Letters Patent the following:

A renewable fuse structure comprising an outer tubular housing of insulating material, means providing a continuous shoulder in the bore of 20 said tubular housing spaced inwardly from one end, and internal threads in the wall of said bore adjacent the other end; and a supporting assembly for a fusible link and including contact blades having narrow tongues extending into the 25 tubular housing, an end disc with a slot receiving and closely fitting one of said tongues, a threaded head in the bore of the tubular housing with a slot receiving and closely fitting the other of said tongues, an insulating spacer member, said 30 tongues and spacer member having aligned apertures, and bolts passing through the apertures and effective for holding the disc and the head respectively clamped between the spacer member and the shoulders on said contact blades and for 35 holding a fusible link in conductive relation to said contact blades, one of said threads being of less depth than the groove engaged thereby so that a portion of the latter remains open and establishes communication between the interior 40 of the tubular housing and the atmosphere; said assembly with the disc foremost being insertable through the threaded end of the tubular housing and the assembly being rotatable through turning of a contact blade to engage the threads of 45 said head with said internal threads for holding said disc in sealing contact against said flange.

JOHN B. GRIFFITH.
